(57) **ABSTRACT**

An inductor device includes a first wire, a second wire, and a third wire. The first wire includes a plurality of first sub-wires. The second wire includes a plurality of second sub-wires. The sequence of the first sub-wires and the second sub-wires is that at least two first sub-wires of the first sub-wires and at least one second sub-wires of the second sub-wires are disposed to each other in an interlaced manner. The third wire is disposed adjacent to at least two first sub-wires of the first sub-wires.

INDUCTOR DEVICE

RELATED APPLICATIONS

This application claims priority to Taiwan Application Serial Number 109110870, filed Mar. 30, 2020, which is herein incorporated by reference.

BACKGROUND

Field of Invention

The present disclosure relates to an electronic device. More particularly, the present disclosure relates to an inductor device.

Description of Related Art

Forms of structures of transformers and inductors are usually spiral structures, symmetrical and interlaced structures, or stacked structures. If forms of structures of transformers and inductors are symmetrical and interlaced structures, the quality value (Q value) is low due to the interlaced structure. The crossing of the interlaced structure in transformers and inductors induces consumption and low inductance. In addition, if the forms of structures of transformers and inductors are stacked structures, the quality value (Q value) will be sacrificed substantially. As a result, the application ranges of the above transformers and inductors are limited.

SUMMARY

In order to resolve the above problems, one aspect of the present disclosure provides an inductor device. The inductor device includes a first wire, a second wire, and a third wire. The first wire includes a plurality of first sub-wires. The second wire includes a plurality of second sub-wires. The sequence of the first sub-wires and the second sub-wires is that at least two first sub-wires of the first sub-wires and at least one second sub-wire of the second sub-wires are disposed to each other in an interlaced manner. The third wire is disposed adjacent to at least two first sub-wires of the first sub-wires.

It is to be understood that both the foregoing general description and the following detailed description are by examples, and are intended to provide further explanation of the invention as claimed.

BRIEF DESCRIPTION OF THE DRAWINGS

The accompanying drawings are included to provide a further understanding of the invention, and are incorporated in and constitute a part of this specification. The drawings illustrate embodiments of the invention and, together with the description, serve to explain the principles of the invention. In the drawings,

FIG. 1 depicts a schematic diagram of an inductor device according to one embodiment of the present disclosure;

FIG. 2 depicts a schematic diagram of partial structure of the inductor device shown in FIG. 1 according to another embodiment of the present disclosure;

FIG. 3 depicts a schematic diagram of partial structure of the inductor device shown in FIG. 1 according to another embodiment of the present disclosure;

FIG. 4 depicts a schematic diagram of an inductor device according to one embodiment of the present disclosure;

2

FIG. 5 depicts a schematic diagram of an inductor device according to one embodiment of the present disclosure; and

FIG. 6 depicts a schematic diagram of experimental data of an inductor device according to one embodiment of the present disclosure.

According to the usual mode of operation, various features and elements in the figures have not been drawn to scale, which are drawn to the best way to present specific features and elements related to the disclosure. In addition, 10 among the different figures, the same or similar element symbols refer to similar elements/components.

DESCRIPTION OF THE EMBODIMENTS

15 FIG. 1 depicts a schematic diagram of an inductor device according to one embodiment of the present disclosure. As shown in the figure, the inductor device **1000** includes a first wire **1100**, a second wire **1200**, and a third wire **1300**. The first wire **1100** includes a plurality of first sub-wires **1110**, **1120**, **1130**, **1140**, **1150**. The second wire **1200** includes a plurality of second sub-wires **1210**, **1220**, **1230**, **1240**, **1250**.

20 For facilitating the understanding of the structure of the inductor device **1000**, reference is now made to FIGS. 1-3. FIGS. 2-3 depict schematic diagram of partial structure of 25 the inductor device shown in FIG. 1 according to another embodiment of the present disclosure. As shown in the figure, the sequence of the first sub-wires **1110**-**1150** and the second sub-wires **1210**-**1250** is that “at least two first sub-wires of the first sub-wires **1110**-**1150** and at least one 30 of second sub-wires of the second sub-wires **1210**-**1250** are disposed in an interlaced manner.” For example, the sequence of the first sub-wires **1110**-**1150** and the second sub-wires **1210**-**1250** is “the first sub-wires **1110**, **1120**, the second sub-wire **1210**, the first sub-wires **1130**, **1140**, and the second sub-wire **1220**.”

35 The third wire **1300** is disposed adjacent to at least two first sub-wires of the first sub-wires **1110**-**1150**. For example, the third wire **1300** is disposed adjacent to at least two first sub-wires **1110**, **1120** of the first sub-wires **1110**-**1150**. However, the present disclosure is not intended 40 to be limited to the above-mentioned embodiments. In some embodiments, the third wire **1300** can be disposed adjacent to at least two first sub-wires **1130**, **1140** depending on actual requirements.

45 In one embodiment, the first wire **1100** and the second wire **1200** are disposed on the first layer, and the third wire **1300** is disposed on the second layer. In another embodiment, the first layer is different from the second layer. For example, the first wire **1100** and the second wire **1200** can 50 be disposed on a lower layer of the inductor device **1000**, and the third wire **1300** can be disposed on an upper layer of the inductor device **1000**.

55 In one embodiment, the third wire **1300** partially overlaps at least one first sub-wire of the first sub-wires **1110**-**1150**. For example, in a direction which is perpendicular to the first wire **1100**, the third wire **1300** partially overlaps at least one first sub-wire **1110** of the first sub-wires **1110**-**1150**. However, the present disclosure is not intended to be limited to the above-mentioned embodiments. In some embodiments, the third wire **1300** can partially overlap the first sub-wire **1130** depending on actual requirements.

60 In one embodiment, the third wire **1300** can totally overlap at least one first sub-wire of the first sub-wires **1110**-**1150**. For example, in a direction which is perpendicular to the first wire **1100**, the third wire **1300** can totally overlap at least one first sub-wire **1110** of the first sub-wires **1110**-**1150**. In another embodiment, as shown in FIG. 1, the

third wire **1300** is disposed at an outside of the inductor device **1000**. However, the present disclosure is not intended to be limited to the above-mentioned embodiments. In some embodiments, the third wire **1300** can totally overlap the first sub-wire **1130** depending on actual requirements.

In one embodiment, the third wire **1300** is disposed between at least two first sub-wires of the first sub-wires **1110~1150**. For example, in a direction which is perpendicular to the first wire **1100**, the third wire **1300** can be disposed between at least two first sub-wires **1110**, **1120** of the first sub-wires **1110~1150**. However, the present disclosure is not intended to be limited to the above-mentioned embodiments. In some embodiments, the third wire **1300** can be disposed between at least two first sub-wires **1130**, **1140** of the first sub-wires **1110~1150** depending on actual requirements.

In one embodiment, the inductor device **1000** further includes a connection element **1400**. The connection element **1400** is coupled to the third wire **1300** and a second sub-wire which is at an inner side of the second sub-wires **1210~1250**. For example, the connection element **1400** is coupled to the third wire **1300**, and coupled to the second sub-wire **1250** which is at an inner side of the second sub-wires **1210~1250**.

In one embodiment, the first wires **1110~1150** and the second wires **1210~1250** are disposed on a first layer, and the third wire **1300** and the connection element **1400** are disposed on a second layer. In one embodiment, the connection element **1400** crosses the first sub-wires **1110~1150** and the second sub-wires **1210~1250** at the same time. For example, the first wires **1110~1150** and the second wires **1210~1250** are disposed on a lower layer, and the third wire **1300** and the connection element **1400** are disposed on an upper layer. As shown in the figure, the connection element **1400** which is disposed on the upper layer crosses the first sub-wires **1110~1150** and the second sub-wires **1210~1250** which are disposed on the lower layer at the same time.

Referring to FIG. 1, the second sub-wires **1210~1250** are wound to form a plurality of wires at an innermost side of the inductor device **1000**. For example, at the outside part of the inductor device **1000**, a sequence of the first sub-wires **1110~1150** and the second sub-wires **1210~1250** is “the first sub-wire **1110**, the first sub-wire **1120**, the second sub-wire **1210**, etc.” At the innermost side of the inductor device **1000**, the second sub-wires **1230**, **1240**, and **1250** are wound to form a plurality of wires.

In one embodiment, the inductor device **1000** further includes a first input/output terminal **1500**. The first input/output terminal **1500** is disposed at a first side of the inductor device **1000**, and located at the first sub-wire which is at an outer side of the first sub-wires **1110~1150**. For example, the first input/output terminal **1500** is disposed at an upper side of the inductor device **1000**, and located at the first sub-wire **1110** which is at an outer side of the first sub-wires **1110~1150**. In another embodiment, the first input/output terminal **1500** and the third wire **1300** are overlapped to each other. For example, in a direction which is perpendicular to the first wire **1100**, the first input/output terminal **1500** and the third wire **1300** are overlapped to each other.

In one embodiment, the inductor device **1000** further includes a second input/output terminal **1600**. The second input/output terminal **1600** is disposed at a second side of the inductor device **1000**, and located at the second sub-wire which is at an outer side of the second sub-wires **1210~1250**. For example, the second input/output terminal **1600** is disposed at a lower side of the inductor device **1000**, and

located at the second sub-wire **1210** which is at an outer side of the second sub-wires **1210~1250**.

In one embodiment, the inductor device **1000** further includes a third input/output terminal **1700**. The third input/output terminal **1700** is disposed at a second side of the inductor device **1000**, and located at the third wire **1300**. For example, the third input/output terminal **1700** is disposed at a lower side of the inductor device **1000**, and located at the third wire **1300**.

10 In one embodiment, the first sub-wires **1110~1150** are coupled to each other at the first side of the inductor device **1000** in an interlaced manner. For example, the first sub-wires **1110~1150** are coupled to each other at an upper side of the inductor device **1000** in an interlaced manner. Specifically, the first sub-wire **1120** is coupled to the first sub-wire **1130** through the connection element **1160** at the upper side. In addition, the first sub-wire **1140** is coupled to the first sub-wire **1150** through the connection element **1170** at the upper side.

20 In one embodiment, the second sub-wires **1210~1250** are coupled to each other at a second side of the inductor device **1000** in an interlaced manner. For example, the second sub-wires **1210~1250** are coupled to each other at a lower side of the inductor device **1000** in an interlaced manner.

25 Specifically, the second sub-wire **1210** is coupled to the second sub-wire **1220** through the connection element **1180** at the lower side. In addition, the second sub-wire **1220** is coupled to the second sub-wire **1230** through the connection element **1190** at the lower side. Besides, the second sub-wire **1220** crosses the first sub-wire **1150** through the connection element **1190** at the lower side of the inductor device **1000**, and is coupled to the second sub-wire **1230** in an interlaced manner.

30 In one embodiment, part of the structure of the inductor device **1000** is a symmetrical and interlaced structure. Another part of the structure of the inductor device **1000** is disposed in a spiral structure, and is stacked above the symmetrical and interlaced structure or stacked below the symmetrical and interlaced structure. For example, the first wire **1100** and the second wire **1200** of the inductor device **1000** is a symmetrical and interlaced structure (they can be coupled to each other in an interlaced manner through the connection elements **1160**, **1170**, **1180**, **1190**), and the third wire **1300** is a spiral structure and is stacked above the first wire **1100** and the second wire **1200** or stacked below the first wire **1100** and the second wire **1200**.

35 FIG. 4 depicts a schematic diagram of an inductor device according to one embodiment of the present disclosure. Compared with the inductor device **1000** in FIG. 1, the disposition of the third sub-wire **1300A** of the inductor device **1000A** is different. For example, the third sub-wire **1300A** is wound toward the innermost side of the inductor device **1000A** at the upper and the lower side of the inductor device **1000A**, and the third sub-wire **1300A** can be disposed 40 above the first sub-wire **1130A** at the left and the right side of the inductor device **1000A**. Besides, the inductor device **1000A** further includes a connection element **1175A**. The connection element **1175A** couples the second sub-wire **1230A** and the second sub-wire **1240A** at the upper side.

45 FIG. 5 depicts a schematic diagram of an inductor device according to one embodiment of the present disclosure. Compared with the inductor device **1000** in FIG. 1, the disposition of the third sub-wire **1300B** of the inductor device **1000B** is different. For example, one terminal of the third sub-wire **1300B** is coupled to the second sub-wire **1240B** which is located at the innermost side of the inductor device **1000B** directly, and another terminal of the third

sub-wire **1300B** can be used as an input/output terminal **1700B**. In addition, the inductor device **10008** further includes a connection element **1175B**. The connection element **11758** couples the second sub-wire **12308** and the second sub-wire **1240B** at the upper side.

FIG. 6 depicts a schematic diagram of experimental data of the inductor device according to one embodiment of the present disclosure. The diagram of experimental data illustrates quality factors (Q) of the inductor device in different frequency. As shown in the figure, the experimental curves of quality factors (Q) of the first wire **1100** and the second wire **1200** of the inductor device **1000** of the present disclosure are C1, C2. In addition to that, the experimental curves of quality factors of two wires of traditional inductor device are C3, C4. It can be seen from the experimental data in FIG. 6 that the quality factors of the first wire **1100** and the second wire **1200** of the inductor device **1000** are 7.7 and 7.3 respectively. Compare to that, the quality factors of two wires of traditional inductor device are 5.9 and 5.3 respectively. Therefore, the design of the structure of the inductor device in the present disclosure can enhance the efficiency of the inductor device. However, the present disclosure is not limited to the values disclosed in the above-mentioned embodiment, and a person of ordinary skilled in the art may use a suitable value depending on actual requirements for achieving a better efficiency.

Although the present invention has been described in considerable detail with reference to certain embodiments thereof, other embodiments are possible. Therefore, the spirit and scope of the appended claims should not be limited to the description of the embodiments contained herein.

It will be apparent to those skilled in the art that various modifications and variations can be made to the structure of the present invention without departing from the scope or spirit of the invention. In view of the foregoing, it is intended that the present invention cover modifications and variations of this invention provided they fall within the scope of the following claims and their equivalents.

What is claimed is:

1. A inductor device, comprising:
a first wire, comprising:

a plurality of first sub-wires;
a second wire, comprising:

a plurality of second sub-wires, wherein an arranged sequence of the first sub-wires and the second sub-wires comprises one of at least two first sub-wire of the first sub-wires, another one of at least two first sub-wire of the first sub-wires, and at least one of second sub-wire of the second sub-wires; and

a third wire, disposed adjacent to the at least two first sub-wire of the first sub-wires, wherein the third wire partially overlaps at least two of the first sub-wires.

2. The inductor device of claim 1, wherein the first wire and the second wire are disposed on a first layer, and the third wire is disposed on a second layer.

3. The inductor device of claim 2, wherein the first layer is different from the second layer.

4. The inductor device of claim 3, wherein the third wire totally overlaps at least one of first sub-wire of the first sub-wires.

5. The inductor device of claim 1, wherein the third wire is disposed at an outside of the inductor device.

6. The inductor device of claim 1, wherein the third wire is disposed between the at least two first sub-wires of the first sub-wires.

7. The inductor device of claim 1, further comprising: a connection element, coupled to the third wire and the second sub-wire which is at an inner side of the second sub-wires.

8. The inductor device of claim 7, wherein the first wire and the second wire are disposed on a first layer, and the third wire and the connection element are disposed on a second layer.

9. The inductor device of claim 8, wherein the connection element crosses the first sub-wires and the second sub-wires.

10. The inductor device of claim 1, wherein the second sub-wires are winded to form a plurality of wires at an innermost side of the inductor device.

11. The inductor device of claim 1, further comprising: a first input/output terminal, disposed at a first side of the inductor device, and located at the first sub-wire which is at an outer side of the first sub-wires.

12. The inductor device of claim 11, wherein the first input/output terminal and the third wire are overlapped to each other.

13. The inductor device of claim 12, further comprising: a second input/output terminal, disposed at a second side of the inductor device, and located at the second sub-wire which is at an outer side of the second sub-wires.

14. The inductor device of claim 13, further comprising: a third input/output terminal, disposed at the second side of the inductor device, and located at the third wire.

15. The inductor device of claim 14, wherein the first sub-wires are coupled to each other at the first side of the inductor device in an interlaced manner.

16. The inductor device of claim 15, wherein the second sub-wires are coupled to each other at the second side of the inductor device in an interlaced manner.

17. The inductor device of claim 16, wherein the second sub-wires cross and is coupled to the first sub-wires the second side of the inductor device in an interlaced manner.
